SHOE SEWING MACHINE

Carl F. Whitaker, Beverly, Mass., assignor to
United Shoe Machinery Corporation, Paterson,
N. J., a corporation of New Jersey

Application June 14, 1933, Serial No. 675,739

11 Claims. (Cl. 112—45)

The present invention relates to wax thread sewing machines, and more particularly to improvements in channel forming and work guiding devices for McKay type shoe sewing machines, 5 which type of machine comprises a straight hook needle, a rotary horn arranged to extend within and support the shoe, and a needle threading whirl located in the horn.

In machines of the McKay type, due to the 10 necessity of operating the needle, feed point, and presser-foot all from the side of the work opposite the rotary horn, the use of a channelling knife and an edge gage is rendered difficult. In sewing women's high arch shoes, the difficulty is increased by the relatively abrupt curvature 15 between the forepart and the shank which causes large variations in the positions of the operating devices when engaging this part of the shoe.

The objects of the present invention are to 20 provide on a McKay type sewing machine a channelling knife operating to cut a groove of more nearly uniform depth than possible heretofore while the presser-foot clamps the work, and a suitable edge gage acting to guide the knife 25 at a fixed distance from the edge of the sole.

With these objects in view, a feature of the 30 present invention contemplates the provision in a McKay type shoe sewing machine of a channelling knife operated jointly by the presser-foot and feed point to form a groove of uniform depth. A further feature of the present invention contemplates a construction in which the distance 35 from the point of operation of the channelling knife to the edge of the sole is determined by an edge gage resiliently mounted on the presser-foot to permit it to yieldingly engage the shoe, so that it will guide the edge of the shoe sole evenly along the instep portion of the shoe where the upper projects beyond the sole edge.

40 Further features of the invention consist of certain constructions, arrangements and combinations of parts, the advantages of which will be obvious to those skilled in the art from the following description.

45 In the drawings illustrating the invention in its preferred form, Fig. 1 is a view in front elevation of a portion, including the stitch forming and work feeding devices, of a sewing machine embodying the present invention, parts being broken away and shown in section; Fig. 2 is a corresponding view on an enlarged scale of a portion 50 of the mechanism shown in Fig. 1; Fig. 3 is a view in side elevation of the parts shown in Fig. 2, looking from the right; Fig. 4 is a sectional view taken along the line 4—4 of Fig. 2; Fig. 5

is a view in elevation on an enlarged scale of the feed point and a portion of the channelling knife shown in Fig. 2; Fig. 6 is a plan view indicating the relation of the feed point and channelling knife, looking in the direction of the arrow 6 in Fig. 5; and Fig. 7 is a sectional view, taken on the line 7—7 of Fig. 1.

5 The machine illustrated in the drawings comprises a straight hook needle 2, a rotary work supporting horn 4, having a needle threading 10 whirl 6, a presser-foot 8, a feed point 10, a rotary shuttle 12, and a loop spreader 14 to open the loop of thread for engagement by the beak of the shuttle. The presser-foot is actuated intermittently to clamp and release the work while 15 the feed point 10 engages and feeds the work alternately with the clamping action of the presser-foot, as is usual in this type of machine.

The presser-foot 8 is supported at the end of a vertical reciprocating presser-foot bar 16. The 20 presser-foot is resiliently held in a downward position and is intermittently retracted to release the work by mechanism indicated generally at 18, which in turn is operated in suitable timed relation with the other stitch-forming devices. 25 The feed point 10 is clamped at the lower end of a carrier 20 slidably mounted for vertical movement towards and away from the work in a guide frame 22 which is pivotally mounted at 24 on the main frame of the machine.

30 The frame 22 is oscillated about its pivot to impart feeding movements to the feed point 10 in the line of feed by means of a lever 25 which is loosely mounted on a hub supported at the forward end of a rock shaft 26 oscillated by connections to a main sewing shaft of the machine. The feed point is moved into and from engagement with the work by the sliding movement of the feed point carrier 20 in the frame 22 through 35 connections to the presser-foot actuating mechanism 18. These connections comprise a link 28 pivotally connected at one end to the upper end of the feed point carrier 20 and at the other end to the arm of a bell crank 30 fulcrumed on a shaft 32 secured to an arm 34, a link 36 connected between the other arm of the bell crank 30 and an arm 38 connected with the presser-foot actuating mechanism 18, the arrangement being such that the feed point 40 is moved into engagement with the work while the presser-foot releases the work. The arm 34 which carries the shaft 32 is fixed at one end to a shaft 40 rotatable in the frame of the machine and at the other end is connected to move with the reciprocating presser-foot bar 16.

45

50

55

55

so that the lowermost position of the feed point, while in engagement with the work, is determined at least in part by the position of the presser-foot while clamping the work. All of the parts above briefly referred to are constructed and arranged in substantially the same manner and operated by mechanism similar to that illustrated and described in the patent to Fred Ashworth No. 1,914,936 dated June 20, 1933.

10 In accordance with the present invention a work channelling knife 41 is provided, pivotally mounted between enlarged forked ends of a horizontal arm 42 secured to the lower end of the presser-foot bar 16. The knife 41 is in the form 15 of a substantially straight rod with its lower end sharpened and with a cutting edge parallel to the length of the rod so as to face the work as it is being fed. The upper end of the knife extends through a transverse opening in a cylindrical member 44 loosely rotatable in the enlarged forked end of the arm 42 and clamped in place by a set screw 46 threaded through an axial opening in the cylindrical member. The member 44 is prevented from displacement by 20 the position of the knife between the forked ends of the arm 42 while still permitting free movement of the lower end of the knife in the line of feed. By its mounting on the presser-foot bar, the position of the lower end of the knife is determined by the position of the presser-foot on 25 the work, so that the knife will always cut a stitch receiving groove of uniform depth, regardless of the thickness of the work.

To actuate the knife while the work is clamped 30 against the horn 4 by the presser-foot 8, the feed point 10 is formed with an enlargement 48, loosely surrounding the lower end of the knife to permit relative movement towards and from the work independently of the feed point. When 35 the feed point is raised and back fed, it moves the channelling knife 41 against the work to form a groove; and when the work is released from the presser-foot, the channelling knife is raised slightly and moves with the feed point to 40 assist in feeding the work. To render the machine more effective for sewing women's high arch shoes, the presser-foot engages the work close to the point of operation of the needle, and the feed point and channelling knife operate 45 through a slot 50 in the presser-foot in the line of feed, as shown in Fig. 7.

The feed point is provided with a removable work engaging knife member 52 mounted in a slot formed therein secured in place by means 50 of a screw 54 passing through the feed point. To assist in supporting the knife 52, a pin 56 in the feed point engages a slot in the upper end of the knife 52. When the knife is fixed in place by the screw 54, the lower cutting edge extends 55 in the line of feed and engages the work just in advance of the channelling knife 41. The channelling knife projects into the work deeper than the feed point knife 52, and follows the line of indentations made in the work by the feed point, 60 so that substantially no irregularity in the work is caused by the feed point in feeding the shoe. The feed point, acting in advance of the channelling knife also assists in guiding the channelling knife to form the groove more evenly since 65 the least resistance to the cutting action of the knife is offered along the line of the indentations formed by the feed point knife.

As previously stated, an edge gage 58 is employed to guide the shoe being operated upon. 70 The edge gage is in the form of an arm extend-

ing downwardly at an angle and rearwardly from the front of the machine so as to engage the edge of the shoe sole, as indicated in Figure 3. In sewing the instep portion of a shoe where the upper projects beyond the edge of the sole, the edge gage is permitted to rise from the dot-dash line position of Figure 2, and accommodate itself to the thickness of the sole while still retaining its gaging position, as shown in the solid lines of Figures 2 and 3.

10 The edge gage is pivotally mounted on the outer end of a horizontal stud 60 secured within a passage formed at the upper end of the presser-foot where it joins the presser-foot bar 16. The stud 60 is maintained in position in the presser-foot by a screw 62 threaded through the presser-foot and engaging the stud 60. The stud is formed with an integral flange 63 near its outer end and a block 64 is loosely mounted on the stud between the flange and a washer 66 secured to the end of the stud by a screw 66. The lower edge of the flange 63 is shaped to allow an upward pivotal movement of the block 64 and is provided with a shoulder with which a projecting portion of the block 64 contacts to limit the downward movement of the edge gage 58 and block. The edge gage 58 at its upper end passes through an opening in the block 64 and is secured in place by a screw 70 engaging the edge gage, and the gage is forced downwardly into contact with the shoe by a coiled spring 72, one end of which enters a passage formed in the flange 63 on the stud 60 and the other end of which engages a slot in the block 64. When the arched portion of the shoe is reached, and the edge gage is raised by the bulging upper at the side of the shoe sole, the block 64 rotating on the stud 60, and the spring 72 yielding sufficiently to permit this movement.

Having thus described the invention, what is claimed is:

1. A shoe sewing machine of the McKay type having, in combination, stitch forming and work feeding devices including a straight hook needle, a rotary work supporting horn, a presser-foot for alternately clamping and releasing the work supported by the horn, and a feed point acting on the side of the work engaged by the presser-foot to feed the work when released, a knife operating in the line of feed with the feed point to form a stitch receiving groove in the work, and means for connecting the knife to be operated by the combined movements of the presser-foot and feed point.

2. A shoe sewing machine of the McKay type having, in combination, stitch forming and work feeding devices including a straight hook needle, a rotary work supporting horn, a presser-foot for alternately clamping and releasing the work supported by the horn, and a feed point acting on the side of the work engaged by the presser-foot to feed the work when released, a reciprocating bar on which the presser-foot is mounted, a knife carried by but movable relatively to the bar in the line of feed, and means for connecting the knife to the feed point to actuate the knife against the work while clamped.

3. A sewing machine of the McKay type having, in combination, stitch forming and work feeding devices including a straight hook needle, a rotary work supporting horn, a presser-foot for alternately clamping and releasing the work supported by the horn and a feed point acting on the side of the work engaged by the presser-foot to feed the work when released, a recipro-

cating bar on which the presser-foot is mounted, a knife pivoted to the bar to swing in a plane parallel with the direction of work feed, and means connected to the feed point for actuating the knife against the work during the back feeding movement of the feed point.

4. A sewing machine of the McKay type having, in combination, stitch forming and work feeding devices including a straight hook needle, a rotary work supporting horn, a presser-foot for alternately clamping and releasing the work supported by the horn, and a feed point acting on the side of the work engaged by the presser-foot to feed the work when released, a knife connected to the feed point and movable relative thereto toward and from the work, and means for connecting the knife with the presser-foot to cause the knife to form a stitch receiving groove of uniform depth in the work.

5. A sewing machine of the McKay type having, in combination, stitch forming and work feeding devices including a straight hook needle, a rotary work supporting horn, a presser foot for alternately clamping and releasing the work supported on the horn, and a feed point formed with an edge elongated in the direction of feed acting on the side of the work engaged by the presser-foot to indent and feed the work when released, a knife connected to be operated by the feed point and movable relative thereto toward and from the work, and means for supporting the knife to cause the knife to form a uniform stitch receiving groove in the work coinciding with the surfaces on the work indented by the feed point.

6. A sewing machine of the McKay type having, in combination, stitch forming and work feeding devices including a straight hook needle, a rotary work supporting horn, a presser foot for alternately clamping and releasing the work supported on the horn, a feed point formed with an edge elongated in the direction of feed acting on the side of the work engaged by the presser-foot to indent and feed the work when released, a knife connected to be operated by the feed point and movable relative thereto toward and from the work, and means for supporting the knife with its cutting edge extending into the work deeper than the edge of the feed point to cause the knife to form a uniform stitch receiving groove in the work coinciding with the surfaces on the work indented by the feed point.

7. A shoe sewing machine having, in combination, stitch forming and work feeding devices including a needle, a work support, a presser-foot for alternately clamping and releasing the sole of a shoe supported on the work support and a feed point acting on the side of the shoe sole engaged by the presser-foot to feed the shoe when released, an edge gage movable on the presser-foot while retaining its gaging position, and resilient means for maintaining the edge gage in yielding engagement with the shoe.

8. A shoe sewing machine having, in combina-

tion, stitch forming and work feeding devices including a needle, a work support, a presser-foot for alternately clamping and releasing the sole of a shoe supported on the work support and a feed point acting on the side of the shoe sole engaged by the presser-foot to feed the shoe when released, an edge gage pivotally connected to the presser-foot to permit relative movement at right angles to the line of feed, and resilient means for maintaining the edge gage in position to guide the projecting edge of the shoe sole and at the same time permitting it to yield when engaged by the upper along the instep portion of the shoe.

9. A shoe sewing machine having, in combination, stitch forming and work feeding devices including a straight hook needle, a rotary work supporting horn, a presser-foot for alternately clamping and releasing the sole of a shoe supported on the horn and a feed point acting on the side of the shoe sole engaged by the presser-foot to feed the shoe when released, a reciprocating bar on which the presser-foot is mounted, an edge gage pivoted on the presser-foot bar, and resilient means for maintaining the edge gage in engagement with the shoe.

10. A shoe sewing machine of the McKay type having, in combination, stitch forming and work feeding devices including a straight hook needle, a rotary work supporting horn, a presser-foot having a slotted portion surrounding the point of operation of the needle for alternately clamping and releasing the work supported by the horn and a feed point projecting through the slotted portion of the presser-foot to feed the work when released, a reciprocating bar on which the presser-foot is mounted, a knife pivotally mounted on the bar to swing along the line of feed in the slotted portion of the presser-foot and an edge gage pivotally mounted on the presser-foot bar to swing towards and from the work at the side of the slotted portion of the presser-foot.

11. A shoe sewing machine of the McKay type having, in combination, stitch forming and work feeding devices including a straight hook needle, a rotary work supporting horn, a presser-foot having a slotted portion surrounding the point of operation of the needle for alternately clamping and releasing the work supported by the horn and a feed point projecting through the slotted portion of the presser-foot to feed the work when released, a reciprocating bar on which the presser-foot is mounted, a work grooving knife connected to move with the feed point along the line of feed in the slotted portion of the presser-foot, connections separate from the feed point for actuating the knife relatively to the feed point towards and from the work, and an edge gage pivotally mounted on the presser-foot bar to swing towards and from the work at the side of the slotted portion of the presser-foot.

CARL F. WHITAKER.
